TAPE REEL WEIGHT

Harry S. Dearling, 25 E. 83rd St.,
New York, N.Y. 10028

Filed June 25, 1969, Ser. No. 17,880

Term of patent 14 years

Int. Cl. D14—99

U.S. CL. D26—14

FIG. 1

FIG. 2

FIG. 3

FIG. 4

FIG. 5

FIG. 1 is a perspective of a tape reel weight, showing my new design;

FIG. 2 is a top plan thereof;

FIG. 3 is an elevation thereof;

FIG. 4 is an elevation of a further embodiment of the tape reel weight illustrated in FIG. 1; and

FIG. 5 is a perspective of a still further embodiment of the tape reel weight illustrated in FIG. 1.

I claim:

The ornamental design for a tape reel weight, as shown and described.
